(57) **CLAIM**

The ornamental design for a trailer door, as shown and
described.

DESCRIPTION

FIG. 1 is a top, front, and left side perspective view of a
trailer showing the left side trailer door that embodies our
new design;

FIG. 2 is an enlarged and partial top, front, and left side
perspective view thereof;

FIG. 3 is a top, rear, and left side perspective view thereof;
FIG. 4 is an enlarged and partial top, rear, and left side
perspective view thereof;

FIG. 5 is a left side elevation view; and,

FIG. 6 is an enlarged and partial left side elevation view
thereof.

The broken lines in the drawings illustrate portions of the
trailer door and environmental trailer structures that form no
part of the claimed design. The broken line showings of the
door trim molding surrounding the door panel, door handle
and latch elements, and wood grain etchings do not form
part of the claimed design. The broken lines in dash-dot style
indicates the bounds of the claim. All surfaces that are
shown with shading lines are part of the claimed design.
